TWO HAND SAFETY LEVER

Freeman Barney, Grand Haven, Mich., assignor
to The Challenge Machinery Company, Grand
Haven, Mich., a corporation of Michigan

Application December 28, 1936, Serial No. 117,875

4 Claims. (Cl. 192—131)

This invention relates to a safety lever which, while it may be used with many types of machinery, has been used by me in conjunction with the operation of paper cutting machines.

In machines which are lever operated and in which there are moving parts that are dangerous to the hands of the operator, the present invention is of particular utility as an operation cannot be performed unless both hands of the operator are used, thus insuring against one hand which is not used and being accidentally placed in any position to be injured by the moving parts of the machine, as for example, the knife in paper cutting machines.

An understanding of the present invention and the construction by means of which assurance against injury is attained may be had from the following description taken in connection with the accompanying drawing in which,

Fig. 1 is an elevation of the novel hand lever structure of my invention.

Fig. 2 is a fragmentary side elevation of the upper part thereof, and

Fig. 3 is a transverse section on the plane of line 3—3 of Fig. 1 looking downwardly in the direction indicated by the arrows.

Like reference characters refer to like parts in the different figures of the drawing.

On a suitable stationary or part 1 of the machine to which the hand lever is applied, a ratchet 2 is permanently secured with the ratchet teeth located around the arc of a circle, the center of which is the axis of a shaft 3 which passes through the ratchet member 2 and rearwardly into the machine having suitable connections for moving the cutting knife, in a paper cutting machine, downwardly on counterclockwise rotation of the shaft and for elevating the knife on clockwise rotation thereof. A hand lever 4 is keyed at its lower end to the shaft 3. Preferably its upper portion will consist of a handle section 4a, both the parts 4 and 4a being of tubular form.

A bracket having diverging arms 5 and 6 is secured to either the handle or the shaft or both so as to move therewith. On the lower arm 5 a ratchet engaging dog 7 is mounted on a pivot pin 8 which extends through the arm 5. The dog is at the inner side of the arm 5 and in a position that when turned counterclockwise it engages with the ratchet. An arm 9 is secured to the pivot 8 at the outer side of the bracket arm 5. At the end of the upper bracket arm 6 a bell crank lever is pivotally mounted. It includes a downwardly extending arm 10, con-

nected by a link 11 with the arm 9 previously described, and a horizontal arm 12 to which the lower end portion of a vertical rod 13 is suitably connected, the rod extending for the major portion of its length through the tubular lever 4 and into the lower end of the handle portion 4a.

A horizontal bar 14 passes through slots 15 in opposite sides of the handle 4a, the length of the slots being greater than the width of the bar 14. The upper end of the rod 12 is pivotally connected to the bar 14 midway between its ends.

Two operating bell crank levers are mounted at different vertical positions at opposite sides of the handle 4a. The lower lever has arms 16 and 17, the former extending in a substantially vertical direction and the latter outwardly in a horizontal direction. A link 19 connects the outer end of the arm 17 with one end of the bar 14. The upper lever has vertical and horizontal arms 19 and 20 respectively, the arm 20 extending outwardly in a direction opposite to the extension of the arm 17. A longer link 21 connects the free end of the arm 20 with the opposite end of the bar 14. The two bell crank levers are partly inserted through vertical slots cut in the opposite sides of the tubular handle 4a, and are pivotally connected on suitable pins extending through the handle substantially at the angles of said levers.

A coiled tension spring 22 is connected at one end to the arm 5 and at its opposite end to the arm 12. The force of the spring tends to turn the bell crank lever consisting of arms 16 and 17 in a clockwise direction thereby moving the rod 13 downwardly and tilting the two levers mounted on the handle to the position shown in Fig. 1, wherein the vertical arms 16 and 19 are turned outwardly so as to lie at an angle to the vertical, and extend partly beyond the adjacent opposite sides of the handle 4a. Likewise the action of the spring is to turn the dog 7 into position to engage with the ratchet 2.

To rock the shaft 3 to perform the operation of cutting paper for example, the ratchet 7 must be disengaged. Both hands must be used, one to grasp and turn the arm 19 inwardly and the other to do the same thing to the arm 16. If one arm, 16 or 19, only is operated there will be no disengagement of the dog 7 from the ratchet 2. This insures that both hands of the operator will be engaged with the operating lever and will therefore be safe from injury. In the operation the lever 4 is turned to the left (referring to Fig. 1). To return the lever to its original position both hands are not needed as the dog 55

will slip over the ratchet teeth, but in such case the paper knife is being elevated and there is no danger of injury such as is present when the paper knife is being lowered in the operation of cutting paper.

With the structure described, the rod 13 is located for its major portion within the tubular lever 4, and the bell crank members 16 and 19 are located in narrow slots in the handle 4a which are but slightly wider than the thickness of said arms. The fingers or fleshy part of the hand are thus protected against pinching and there is little or no exposed mechanism with which the operator may come into contact in any manner 15 so as to prevent a liability of injury.

The construction described while of a simple character is one which has proven particularly practical and useful. The invention is defined in the appended claims and is to be considered 20 comprehensive of all forms of structure coming within the scope of the claims.

I claim:

1. In combination, a pivotally mounted tubular lever, a ratchet associated therewith, a spring actuated dog normally engaging the ratchet, a rod located lengthwise of and within said lever for the major portion of its length, means connecting the rod with the dog whereby the dog is disengaged from the ratchet on longitudinal 25 movement of the rod in one direction, a bar extending transversely through the lever, the upper end of said rod being pivotally connected to said bar, two bell crank handle members located in slots in opposite sides of the upper portion of 30 said lever, one above the other, having oppositely extending arms, links connecting said arms with the ends of said bar, and means for pivotally mounting said bell crank levers, said levers having upwardly extending arms located in vertical 35 slots in the upper portion of said lever.

2. Operating means for a ratchet dog associated with a pivotally mounted tubular hand lever comprising, a rod extending longitudinally through the lower portion of said lever, a horizontal bar extending laterally through said lever 45 at the upper end of the rod, the rod having pivotal connection substantially at the midpoint of said bar and said handle having vertical slots through which the bar passes of greater height

than the width of the bar, said bar adapted to slide therein, two bell crank levers located one above the other and at opposite sides of and extending into slots in opposite sides of the upper portion of the lever, means pivotally mounting 5 said bell crank levers on the lever, said bell crank levers having opposite outwardly extending arms, and links connecting the ends of said arms with the ends of said bar.

3. In combination with a movably mounted 10 hand lever of tubular form, a rod extending vertically into said hand lever at the lower portion thereof, said hand lever at its upper end portion having two vertical slots, one above the other in opposite sides thereof, and two additional vertical 15 slots below the first slots directly opposite each other and at the upper end of said rod, a bar extending laterally through the last mentioned slots pivotally connected at substantially its middle point to the upper end of the rod, and operating devices extending one through each of the first mentioned slots and movably mounted on the hand lever, combined with means connecting the same to the opposite ends of said bar whereby longitudinal movement of said rod in a vertical 20 direction requires operation of both of said operating devices.

4. In combination, a tubular hand lever, said lever having vertical slots in opposite sides thereof near its upper end, one of said slots being located above the other, and also slots below the first slots directly opposite each other, a horizontal bar having a width less than the height of said last mentioned slots extending laterally therethrough, a rod pivotally connected at its upper 30 end to said bar extending downwardly through the hand lever from the bar, flat bell crank levers, each having a vertical arm and an outwardly extending arm inserted into the first mentioned slots and pivotally mounted on the hand lever, and links connecting the outer ends of said horizontal arms with the ends of said bar whereby on pivotally turning both of said bell crank levers inwardly so that the vertical arms thereof are brought flush at their outer edges with the outer 35 surface of the hand lever, said horizontal bar and rod attached thereto are lifted vertically.

FREEMAN BARNEY.
